FIG. 7

FIG. 8.

UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

MACHINE AND METHOD FOR SEALING INCANDESCENT LAMPS.

Application filed January 10, 1923. Serial No. 611,831.

To all whom it may concern:

Be it known that I, JOHN JOSEPH HIGGINS, a citizen of the United States, and a resident of East Orange, in the county of Essex and State of New Jersey, have invented a new and useful Improvement in Machines and Methods for Sealing Incandescent Lamps, of which the following is a specification.

10 This invention relates to an improved method and apparatus for uniting the component parts of a lamp and relates particularly to the consolidation of a glass bulb with an exhaust tube.

15 An object of the invention is to provide a method and means for hermetically sealing leading-in wires at the union of two component parts of a lamp.

Another object is to facilitate the operation 20 of consolidating the lamp parts and in reducing the amount of dexterity and skill heretofore required.

A further object is to reduce the time 25 element for the consolidating operation and to increase production and cheapen the cost of manufacture.

Other objects and advantages will be apparent from the following description.

Considerable difficulty arises in the manufacture 30 of incandescent lamps of certain types, such as the miniature lamps, which are often used in portable apparatus employing dry batteries. Heretofore, a common method of uniting the glass parts and sealing-in the leading-in wires, was to position the leading-in wires between the edge 35 of the neck of the bulb and to suitably heat the neck and the end of a glass tube, whereupon the two glass bodies were moved until 40 their plastic portions made contact and a weld was produced by the cohesion of the melted material, the leading-in wires being embedded in the fused portion and, consequently, secured therein when such portion 45 hardened.

The above operation required a relatively high degree of skill, not always obtainable, and, in the event of the improper manipulation of the parts, leaky seals and consequently considerable shrinkage resulted.

The present invention provides a method and apparatus whereby the edge-to-edge or butt-seal is avoided and a tube may be disposed concentrically within the neck of a

bulb, the leading-in wires being positioned 55 between the bulb and the tube and in substantially diametrically opposite relation. Heat may then be applied locally to the neck of the bulb which is softened, as well as the end of the tube disposed therein. A considerable mass of material is, therefore, provided about the neck of the bulb and relatively long portions of the leading-in wires are embedded in this mass, therefore, the area of the leading-in wires in contact with 65 the glass is sufficient to permit the proper wetting of the metal by the glass and, therefore, to reduce the amount of leakage.

In the manufacture of miniature flash lamps, it has heretofore been necessary to 70 form a constriction in the tube which is secured to the bulb, particularly when manufacturing lamps by the so called butt-seal method. The constricted portion is formed by heating a section of the tube until plastic 75 and then elongating the tube, thereby providing a section having a relatively small diameter. This diametrically reduced portion of the tube facilitates the operation of tipping-off or sealing the lamp after it has 80 been evacuated.

In the present invention, however, it is possible to dispense with the operation of forming a constriction since a tube of a relatively small diameter may be employed. 85 Such diameter is approximately that produced at the constriction of the larger-size tubes employed with other methods. The tipping-off may therefore, by reason of the small-calibre tube I am able to employ, be 90 accomplished in a practical and convenient manner at a great saving of labor and time.

This desirable result may be attained since, by my method of sealing, the tube is 95 inserted within the neck of the bulb, and it will be evident that the tube used may be of a diameter reduced by a dimension at least equal to twice the thickness of the wall of the bulb neck.

Another advantage of the invention consists in the proper disposition of the leading-in wires. It has been found that, when the leading-in wires are held in position in opposition to a potential force because of their resiliency, they tend to move, when the tube and bulb neck became softened, thus preventing the proper coherence between the two melted bodies. This condition resulted

in leaks, causing defective lamps and obviously increasing the cost of production.

The present invention provides for the proper positioning of the wires in such a manner that they will be set and firmly disposed against the tube, so that, when the tube and bulb are rendered plastic, no resilient action will exist to disturb the proper union of the two bodies. Furthermore, when the tube and bulb neck, with the interposed wires, have been heated and rendered plastic, the fused material is permitted to flow freely, and an effective union of the parts is produced. However, at the proper moment, a blast of air, preferably heated, is directed through the tube, and a communicating passage or orifice between the tube and bulb is maintained. The bulb may, at this time, be permitted to begin to cool and, by the time the orifice has been formed, the plastic portion has become hardened and a union of the parts produced. After the consolidation of the parts, they may be subjected to an annealing operation in any suitable manner.

I have found that, in order to carry out my method, an apparatus for properly supporting the several elements in a given relation is preferable. Such apparatus may include means for properly retaining the mount, with the leading-in wires thereof properly disposed between the neck of the bulb and the tube. It is desirable to provide grooves or guides for the leading-in wires of such construction that, when the wires are in position to be sealed into the lamp, they will be disposed in close proximity, preferably contiguous to the tube.

Various methods have been employed for uniting the several parts of a lamp, that is, in consolidating the glass exhaust tube with the neck of the glass bulb. In some methods, a tubular member or mandrel is used, the mandrel being inserted into the exhaust tube of the lamp to maintain a communicating passage between the tube and the bulb after the sealing operation has been performed. The removal of the mandrel after sealing necessitated an operation which was more or less difficult and which involved the expenditure of a considerable amount of an operator's time.

In the present invention, a fluid, as, for instance, compressed air, is utilized to maintain the required opening at the seal and provide an orifice between the bulb and the tube after their consolidation.

It has been found, however, that the most desirable results are obtained by introducing the air at a predetermined stage of the sealing-in operation. For example, heat may be applied to the neck of the bulb having the end of an exhaust tube disposed therein, leading-in wires being interposed between the neck and tube. The glass parts

become fused and the molten material is permitted to flow or puddle, thus, the tube and bulb neck are effectively united in a common wall, with the leading-in wires embedded therein.

When this stage is reached, a blast of heated air is directed through the tube and into the bulb, thus preventing a complete closure of the tube at the seal. As the air is discharged into the tube, the consolidated parts are moved from the fire and cooled, and the opening between the bulb and tube is maintained for the subsequent operation of evacuating the bulb.

The bulb, with the exhaust tube united thereto, is then ready to be exhausted. When exhausting a miniature lamp of the most commonly used type, the tipping-off operation may readily be accomplished without forming any constriction in the exhaust tube. If, however, a bulb having a neck of extra-large diameter is employed, the usual constriction may be formed in the exhaust tube in the usual manner.

The filament of a mount, as used in the miniature lamps, must be properly positioned within a bulb. The position of the filament or light source is usually in the plane of the greatest diameter of the bulb.

The manufacture of bulbs for miniature lamps requires a certain amount of accuracy, however, when the bulbs are produced, the necks thereof, although of the proper lineal dimension are not always cut in the proper plane, namely, transversely to the axial line of the neck.

Several machine elements which support the assembled parts of a lamp may be rotated as a unit during the application of heat, which rotation tends toward uniformity at the sealed portion.

My invention, therefore, not only contemplates the provision of mechanism for properly supporting the tube and for disposing a mount in a given relation thereto, but other machine elements for the automatic adjustment of a bulb to position it in a given relation to a mount. Such machine elements may comprise gripping members which secure a bulb about its spherical surface, lifting the edge of the neck portion thereof from a temporary seat and so suspending the bulb that the edge of the neck plays no part in its adjustment with relation to the mount. By the provision of an automatic means for adjusting a bulb, an operator may more rapidly assemble the parts, with the exercise of a minimum amount of skill. The mechanical adjustment of the bulb with respect to the other parts results in a more uniform product.

The invention will be more fully understood by reference to the accompanying drawings, in which:

Fig. 1 is a view, in elevation, of the sev-

eral component parts of a miniature lamp positioned for the sealing operation;

Fig. 2 is a similar view showing the several parts of a lamp after they have been united;

Fig. 3 is a similar view showing the united parts and indicating the position of a nozzle for directing a current of air through the exhaust tube;

Fig. 4 is a view, in elevation, of a head adapted to support the several parts of a lamp for consolidation;

Fig. 5 is an enlarged plan view of the head shown in Fig. 4, the top plate being removed, and shows the jaws in their closed positions to grip the bulb of a lamp and also shows, in dotted lines, the open positions of the jaws;

Fig. 6 is a front elevational view of the upper portion of the head illustrated in Fig. 4 on an enlarged scale, partly in section, to show jaws for gripping leading-in wires;

Fig. 7 is a plan view, partly diagrammatic, of a machine for intermittently rotating heads such as shown in Fig. 4; and,

Fig. 8 is an elevational view of the machine shown in Fig. 7, certain parts being omitted to more clearly illustrate other parts.

A lamp of the character to which the present invention relates may, as shown in Fig. 1, comprise an exhaust tube 10, a mount 11 and a bulb 12. The bulb may be provided with an extended annulus or neck 13, and the tube 10 employed may have an outside diameter slightly less than the inside diameter of the neck 13, sufficient space being provided for the disposition of leading-in wires 14 and 15 of the mount 11, therebetween.

When the several parts have been properly positioned, suitable fires 16, as indicated in dotted lines in Fig. 2, are caused to impinge upon the neck portion of the bulb 12 in which an end 17 of the tube 10 is concentrically disposed. The fires 16, disposed at opposite sides of the work parts, may be employed when the heating operation is performed while the work is not rotated or if it is desired to reduce the time of heating. However, as will be hereinafter shown, only one fire may be used when the work is rotated. The leading-in wires are so placed as to have a portion of their lengths positioned between the inner surface of the neck 13 and the outer surface of the end 17 of tube 10.

The fires 16 are caused to heat locally the component parts of the lamp until they have become plastic with semi-fluid adjacent portions and united by their coherent property. The leading-in wires 13 and 14 will thus become embedded in the molten material. The action occurring is that similar to a union of glass parts by a puddling operation, and the plastic material is heated for a sufficient interval of time and with the

proper intensity to permit the proper and thorough union of the neck portion 13 of the bulb 12 and the end 17 of the tube 10.

When a consolidation of the glass parts has been effected and just as the lamp is removed from the fires, a blast of air, issuing from a nozzle 18, is directed through the exhaust tube 10 and into the bulb 12 for the purpose of preventing a closure of the aperture within the exhaust tube and thus maintaining a communicating orifice 19 for the subsequent exhausting operations.

A preferred mechanism for handling and automatically performing the above operations may comprise a head 21, Fig. 4, comprising a standard or frame of any desirable construction. The one shown may include two vertical support members 23 and 24, the member 24 being of tubular form to constitute a guide bearing to support a shaft, the purpose of which will be later described. The support members are connected, at their lower ends, by a cross-piece 25 and, near their upper ends, by a bridge 26. Integral with the bridge and centrally disposed between the supports 23 and 24, is a sleeve 27 having its vertical axis coincident with the vertical axis of the head. Extending downwardly and suitably secured to the cross-piece 25, is a hollow shaft 28 having a friction wheel or pulley 29 fastened to its lower end.

Extending upwardly and threaded to the cross-piece 25 is a tubular member 31 which is connected, at its upper end, to a cylindrical member or tube holder 32. The tube holder 32 is secured in the sleeve 27 by set screws 30 and is provided with a suitable axially disposed aperture 33 into which an exhaust tube 10 may be inserted, so as to position the interior of the exhaust tube in alignment with a passage 34 in the member 32, which passage is in communication with the interior of the tubular member 31, which, in turn, communicates with the hollow shaft 28. Thus, air may be directed through the lower end of the shaft 28 upwardly through the exhaust tube 10, when positioned in the holder 32. Means for effecting the passage of air will be later described.

The upper end of the tube holder 32 is provided with a seat 35 for temporarily supporting a bulb when positioned with its end thereon. The bulb may, however, be subsequently gripped between a pair of jaws 36 and 37, slidable in guides 38 and 39 of a jaw-carrier 41, the carrier being integral with, or suitably secured to, the upper ends of the support members 23 and 24.

The jaws 36 and 37 may be actuated by a cam plate 42, secured to the upper end of a shaft 43, disposed in the support member 24, the lower end of the shaft 43 being pinned to a collar 44 having an arm 45 integral therewith. A spring 46, secured to

the arm 45 and to a lug 47, integral with the cross-piece 25, serves normally to maintain the cam plate 42 in a position transverse to the path of movement of the jaws 36 and 37, as shown in full lines in Fig. 5. Thus, the jaws, by reason of the spring 46, will be normally maintained in a closed position to grip an object inserted therebetween. The cam plate 42 may be oscillated 10 to engage the shank 48 of the jaw 36 and the shank 49 of the jaw 37, thereby effecting a separation of the jaws for the release of an object. The shaft 43 may be oscillated by the movement of a lever arm 51 secured to the lower end of the shaft 43. The lever may be actuated either by hand or by automatic means including a suitable cam.

In the illustrated embodiment, the lever 20 51 is provided with a roller 52 adapted to engage a suitable cam surface 53 indicated in dotted lines in Fig. 5 and more clearly shown in Fig. 7. A more detailed description will presently be given.

25 When an exhaust tube is positioned in the aperture 33, a mount 11 may be disposed thereover, with the leading-in wires 14 and 15 positioned adjacent the exhaust tube and lengthwise thereof. Suitable grooves 54 and 30 55, see Fig. 6, are provided in the wall of the aperture to receive the lower ends of the leading-in wires.

Heretofore, difficulty has been experienced in properly positioning the leading-35 wires with respect to the exhaust tube, prior to the sealing operation, and it has been found advantageous to maintain a portion of the leading-in wires in close contact with the exhaust tube during the sealing 40 operation. For this purpose, a pair of jaws or pressing members 56 and 57 may be provided to engage the leading-in wires and press them against the exhaust tube. The jaws may be pivoted on pins 58 mounted 45 in the upper end of the tube holder 32. Each jaw may be provided with a slotted arm 59 pinned to the upper ends of rods 61, the lower ends of the rods being secured to a reciprocable sleeve 62, slidably disposed 50 upon the tubular member 31.

The sleeve 62 is normally urged upwardly by a spring 60 disposed between the lower end of the sleeve and the upper side of the cross-piece 25. Thus, the jaws 56 and 57 55 are normally urged toward the axial line of the aperture 33. Laterally projecting finger pieces 63, integral with the sleeve 62, may be provided, whereby an operator may press downwardly upon the sleeve to open the jaws 56 and 57 for the insertion of the exhaust tube and leading-in wires. A release 60 of the sleeve 62 will, therefore, serve to actuate the presser-members 56 and 57 to press the leading-in wires 14 and 15 into 65 contact with the exhaust tube.

After the exhaust tube and leading-in wires have been properly disposed, a bulb 12 may be placed over the mount, with the neck thereof in concentric relation to the upper end 17 of the exhaust tube. Owing to manufacturing inaccuracies, the bulbs, as provided, may not have the edge of the neck thereof uniform, that is, irregularities in the surface may occur. Thus, when a bulb is placed over the end of the exhaust tube 75 and the edge thereof is disposed on the seat 35 of the tube holder 32, the bulb may not be properly positioned to dispose the filament of the mount in proper relation thereto.

For the purpose of properly adjusting the bulb, the jaws 36 and 37 are provided with contacting surfaces 40 of such configuration or with contact points so disposed as to properly engage the outer surface of the bulb, and a closure of the jaws serves to lift 85 the bulb from the seat and properly position and secure it for the sealing-in operation.

One form of machine for carrying the heads 21 through the several stages or operations essential to the sealing-in of a lamp is shown in Figs. 7 and 8. As illustrated, such machine may include a supporting structure or table 70 having a centrally disposed shaft 71 secured in a socket 72. Rotatably disposed upon the shaft 71 is a spider or conveyor 73 having a plurality of arms 74 terminating in hubs 75. Heads 21, such as illustrated in Fig. 4, may have their shafts 28 disposed rotatably in the hubs 75, 100 and the lower portions of the cross pieces 25 may serve to provide bearing surfaces.

The conveyor 71 may be intermittently rotated by means of a Geneva movement 76 comprising the usual slotted member or 105 driven wheel 77 and a driver 78 having a roller 79 to engage slots 81 of the member 77. The member 77 may be suitably secured to the spider 73 and may be rotatable about the shaft 71, a collar 80 being provided to afford a bearing surface and prevent downward movement of the member 77. Motion may be transmitted to the driver 78 from any suitable source of power, for instance, a motor (not shown) through a shaft 82, the 110 driver being mounted on a vertical shaft 83 and provided with a worm wheel 84 disposed in mesh with a worm 85 secured to the driving shaft 82. Rotation of the shaft 82 will, therefore, by virtue of the Geneva 115 movement 76, cause an intermittent rotation of the conveyor 73.

It is desirable to rotate the heads 21 at several of the rest stages of the conveyor 73 throughout a cycle of its movement. At 125 such stages, friction wheels 29 may be engaged by driving wheels 86 located at one or more points adjacent the path of travel of the heads. The driving wheels 86 may be rotated by means of an endless belt 87 130

adapted to engage sheaves 90 secured to the wheels 86, one of which may be secured to a supplemental driving shaft 88. Motion may be translated to the driving shaft 88 through the main driving shaft 82, which is provided with a beveled gear 89 disposed in mesh with a beveled gear 91 secured to a vertical shaft 92. The shaft 92 is geared to the shaft 88 by a spur gear 94 secured to the shaft 92 and disposed in mesh with a gear 95 secured to the shaft 88.

Burners 96, 97, 98 and 99 may be provided at the several rest stages of the conveyor to suitably heat the work parts during their rotation with the heads, when the friction wheels 29 engage the driving wheels. When the several parts have been heated and are uniting, a current of air is directed upwardly from nozzle 18, through shaft 28 and through the exhaust tube 10.

As illustrated in Figs. 7 and 8, air may be received from a pressure line 101 which may be normally closed by reason of a slide valve 102 adapted to close the connection between the supply line 101 and a passage 103 terminating in the nozzle 18, which is so positioned as to lie below the path of movement of the lower end of the passages in the shafts 28 of the heads. Thus, when the heads are successively positioned over the nozzle 18 at the end of a movement, air may be permitted to flow upwardly through the exhaust tube of a lamp to maintain an opening between the exhaust tube and the bulb. It is of considerable importance to effect this discharge of air at the proper point and for a given time interval.

It has been found that a quick and relatively intense blast of air is desirable, and means are provided for operating the valve 102 to effect this proper discharge. Such means may consist of a slide rod 104 having a transverse aperture 105 therethrough, the rod being movable to make communication between the line 101 and the passage 103. The slide rod 104 is, however, normally urged to close the passage through the action of a spring 106, disposed between a collar 107 secured to the rod and an end of a bearing 108, in which the rod 104 may be reciprocated. By reason of the spring 106, an end 109 of the slide rod 104 is maintained in contact with the surface of a cam wheel 111, having a raised portion 112 thereon.

The cam 111 may be secured to the shaft 83 and thus rotated with the driver 78. The cam may be properly positioned so that just before the driver starts to move a head from the fires, the raised portion 112 of the cam 111 will engage the slide rod 104, thus opening the valve 102 to permit a blast of air to be discharged upwardly through the exhaust tube. The discharge is of relatively short duration, owing to the shape and movement of the cam, which permits a re-

verse movement of the rod 104 and a closure of the valve 102.

As above stated, the jaws 36 and 37 of a head may be automatically opened through the action of the lever arm 51 when engaged with the cam surface 53. When a head is at the initial or loading position, as shown in Fig. 7, a cam member having a surface 53 may be properly positioned with respect to the moving heads and may be secured to the stationary structure of the machine. However, when a head returns to the initial or loading position indicated by the letter A, it is necessary to provide a means for properly aligning the head to position it for engagement with the cam 53. Means for accomplishing this may comprise a brake device including segment 114 positioned adjacent the path of movement of the heads, and the rollers 29 may be provided with flattened portions 115.

The segment 114 may be mounted on a pin 116 and resiliently urged toward the path of the heads by a spring 117. Thus, when conveyor 73 moves a head from the position indicated by the letter F, the roller 29 will engage the segment 114. The flat portion 115 on the roller 29, making contact with the surface 118 of the segment, will prevent further rotation of the head and align it, so that, as the conveyor moves the head to the position A, the roller 52 of the lever arm 51 will engage the cam surface 53 and, by the time the head is in position for the loading operation, the jaws 36 and 37 will be opened.

In operation, assuming that a head is in position at the stage indicated by the letter A, it will, by reason of the cooperating machine elements, be properly aligned for the loading operation, and the jaws 36 and 37 will be in their open positions.

The operator then actuates the presser-members 56 and 57 by a downward pressure upon the finger pieces 63. While the presser-members are open, the operator may insert an exhaust tube 10 into the aperture 33. The length of the aperture should be such as to cause the end 17 of the exhaust tube to be exposed, that is, to extend above the seat 35. The leading-in wires 14 and 15 of a mount 11 are disposed in the apertures 54 and 55 respectively. The mount may thus be properly positioned, the finger pieces 63 released and the presser members 56 and 57 caused to make contact with portions of the leading-in wires adjacent the end 17 of the exhaust tube. Thus, the leading-in wires will be held firmly in position and their tendency to spring away from the exhaust tube during subsequent operations will be eliminated.

A bulb may then be disposed with the neck thereof about the exhaust tube and leading-in wires and may be temporarily

positioned by resting the neck thereof upon the seat 35. After these manual operations have been performed, the conveyor moves and, as the head is carried away from the loading position, the lever arm 51 is, by reason of the receding cam surface 53, permitted to take its normal position through the action of the spring 46 and the jaws close upon the bulb 12. This action of the jaws lifts the bulb from the seat 35, properly aligns and positions it with the filament or light source of the amount in a given relative position, preferably in the plane of the greatest diameter 15 of the bulb.

The head is then moved to its next stationary stage, which is indicated by the letter B, and rotated while fires 96 are caused to impinge upon and heat the concentrically 20 disposed work parts. During this stationary stage of the conveyor, another head is loaded. At the next stationary position indicated by the letter C, fires are again caused to locally heat the work parts, rendering them more plastic. The same operation is performed at the stage or station D, however, at this point, the proper union of the several parts will have been attained and, just before the conveyor begins to 25 travel and the head leaves the fire, the valve 106 is operated to discharge a blast of air upwardly through the exhaust tube 10 in order to maintain communication between the bulb and the tube for exhausting purposes. At the next station E, the burner 35 99 may cause a relatively low-temperature fire to impinge upon the work for an annealing operation. At the final stage F, a time interval is provided for a partial cooling of the work before removal at the station A.

It will be appreciated that the present invention provides for the expeditious and economical production of miniature lamps. Furthermore, a minimum amount of manual operations and comparatively small degree 45 of skill is required for the production of such lamps.

Although a preferred form of the invention is shown and described, it will be understood that modifications may be made therein without departing from the spirit and scope 50 of the appended claims.

What is claimed is:

- 55 1. A sealing-in machine for incandescent electric lamps comprising means for supporting a bulb, means for automatically securing a bulb, means for supporting an exhaust tube with an end in the neck of said bulb, means for supporting a mount with the leading-in wires thereof positioned between the walls of said bulb and tube and means for heating said bulb and tube to effect a consolidation thereof.
- 60 65 2. A sealing-in machine for incandescent

electric lamps comprising slidable members for engaging and supporting a bulb, a support for an exhaust tube to hold the same with an end disposed in the neck of said bulb, means for maintaining a mount in a given relation to said bulb, means for retaining portions of the leading-in wires of said mount in a given relation to said tube and bulb and means for heating said positioned bulb and tube to effect a consolidation thereof. 70

3. A sealing-in machine for incandescent electric lamps comprising means for supporting a bulb and exhaust tube with portions thereof in overlapped concentric relation, means for pressing the leading-in wires of a mount in contact with said exhaust tube and means for heating said positioned bulb and tube to effect a consolidation thereof. 80

4. A sealing-in machine for incandescent electric lamps comprising reciprocable members to engage and support a bulb, a tubular member to receive an exhaust tube and hold the same with an end thereof in the neck of said bulb, means for supporting a mount with the leading-in wires thereof positioned between said bulb and tube, means for heating said bulb and tube to effect a consolidation thereof and means for preventing a closure of the passage in said exhaust tube during the consolidation. 90

5. A sealing-in machine for incandescent electric lamps comprising a pair of jaws, means to automatically actuate said jaws to secure and support a bulb, means for supporting an exhaust tube with an end thereof in the neck of said bulb, means for maintaining a mount in a given relation to said bulb, means for retaining the leading-in wires of said mount in a given relation to said tube and bulb, means for heating said positioned bulb and tube to effect a consolidation thereof and means for preventing a closure of the passage in said exhaust tube during the heating operation. 100

6. A sealing-in machine for miniature incandescent electric lamps comprising means for supporting a bulb and exhaust tube with portions thereof overlapping, means for supporting a mount with the leading-in wires thereof positioned between said bulb and tube, means for pressing said wires against said tube, means for heating said bulb and tube to effect a consolidation thereof and means for forcing air through said exhaust tube before said heated portion solidifies. 110

7. A sealing-in machine for miniature incandescent electric lamps comprising means for supporting an exhaust tube, means for supporting a mount in axial alignment with said exhaust tube, means for temporarily supporting a bulb with the neck portion thereof in overlapping relation to an end of said exhaust tube, means for automatically 115

ly adjusting said bulb in a concentric position with respect to said tube and mount and means for consolidating said bulb and tube.

8. A sealing-in machine for miniature incandescent electric lamps comprising means for supporting an exhaust tube, means for supporting a mount in axial alignment with said exhaust tube, means for temporarily supporting a bulb with the neck portion thereof in over-lapping relation to an end of said exhaust tube, means for automatically adjusting said bulb in a given concentric position with respect to said mount, means for heating said positioned tube and bulb to effect a consolidation thereof and means for discharging air through said exhaust tube to maintain the passage in said exhaust tube open.

9. A sealing-in machine for incandescent electric lamps comprising means for supporting a bulb and exhaust tube with portions thereof overlapping, means for supporting a mount with the leading-in wires thereof positioned between said bulb and tube, means for pressing said wires against said tube, means for heating said bulb and tube to effect a consolidation thereof and means for automatically discharging air into said exhaust tube.

10. A sealing-in machine for incandescent electric lamps comprising means for supporting a bulb and an exhaust tube with portions thereof overlapping, means for supporting a mount with the leading-in wires thereof positioned between said bulb and tube, presser jaws for maintaining said leading-in wires in contact with said exhaust tube and means for heating said bulb and tube to effect a consolidation thereof.

11. A sealing-in machine for incandescent electric lamps comprising a head for supporting a bulb and an exhaust tube with portions thereof overlapping, means for supporting a mount with the leading-in wires thereof positioned between said bulb and tube, means for moving said head to convey lamp parts intermittently in a series of stages, means for heating said bulb and tube to at least one of said stages to consolidate said parts and means for effecting a discharge of air through said exhaust tube at a predetermined stage throughout the path of movement of said lamp parts.

12. A sealing-in machine for incandescent electric lamps comprising means for supporting a bulb and exhaust tube with portions thereof in overlapped concentric relation, a member having apertures to receive the leading-in wires of mounts, presser jaws for maintaining the said leading-in wires in contact with said exhaust tube, means for moving said positioned lamp parts in a series of intermittent stages, means for applying heat to said exhaust

tube and bulb at at least one of said stages and means for effecting a discharge of air through said exhaust tube prior to the movement of said lamp parts from a stationary stage.

13. A sealing-in machine for incandescent electric lamps comprising slidable jaws, means for operating said jaws to secure a bulb, means for supporting an exhaust tube in concentric relation to the neck of said bulb, means for supporting a mount with leading-in wires disposed adjacent said exhaust tube, pressure jaws for maintaining the leading-in wires in a given relation to said exhaust tube and means for heating said positioned bulb and tube to effect a consolidation thereof.

14. A sealing-in machine comprising a pair of slidable jaws, means for operating said jaws to secure a bulb means for supporting an exhaust tube with an end thereof disposed in the neck of said bulb, a member having apertures to receive the leading-in wires of a mount, presser jaws for maintaining said leading-in wires in close relation to said exhaust tube and means for heating said exhaust tube and bulb to effect a consolidation thereof.

15. A sealing-in machine for incandescent electric lamps comprising a pair of slid- 65 able jaws for securing a bulb, a member having a tubular aperture to receive and support an exhaust tube in a given relation to a bulb secured in said jaws, grooves in said member at opposite sides of said aperture for the entrance of leading-in wires of a mount, presser members for maintaining said leading-in wires in close relation to said exhaust tube, means for heating said bulb and tube to effect a consolidation thereof and means for automatically 100 discharging a blast of air through said exhaust tube.

16. The method of uniting lamp parts which comprises positioning a bulb and a tube with overlapping concentric portions, positioning a mount with leading-in wires thereof disposed between said portions, heating to render plastic said portions to effect their consolidation, directing a blast 110 of air into said exhaust tube and holding the leading-in wires against the tube during the hardening of the plastic portion.

17. The method of uniting lamp parts which comprises positioning a bulb and a tube with overlapping concentric portions positioning a mount with leading-in wires thereof disposed between said portions, heating to render plastic said portions to effect their consolidation, directing a blast 120 of air into said exhaust tube and pressing the leading-in wires in contact with the exhaust tube during the cooling of said plastic portions.

18. The method of uniting lamp parts 130

- which comprises positioning a tube and a bulb with overlapping concentric portions, positioning a mount with the leading-in wires thereof placed between said portions, holding the leading-in wires against the exterior surface of the tube to prevent lateral movement of the wires during said cooling.
- 5 heating to render plastic said portions to effect their consolidation, creating a fluid pressure within the tube and bulb during the cooling of said plastic portions and
- In testimony whereof, I have hereunto subscribed my name this 9th day of January, 1923.

JOHN JOSEPH HIGGINS.
